ILLUMINATED DISPLAY CASE

George J. Hopkins, Kendallville, Ind., assignor
to McCray Refrigerator Company, Kendall-
ville, Ind., a corporation of Indiana

Application June 2, 1933. Serial No. 674,076

8 Claims. (Cl. 240—6)

The present invention relates to illuminated display cases and more particularly to means for preventing visible reflection of the illuminating means upon the glass panes of such display cases.

The main objects of the invention are to provide a novel type of illuminated display case; to provide effective and efficient means for illuminating such display cases; to provide means for illuminating the interior of display refrigerator cases without impairing the efficiency of the refrigerator; to provide concealed means for illuminating the interior of a display case; to provide means for illuminating the interior of a display case but preventing visible reflection of the illuminating means upon the glass panes of such display case; and, to provide a display case of the character above indicated which is novel in construction, utilitarian in use and attractive in appearance.

20 An illustrative embodiment of the invention is shown in the accompanying drawings, wherein:

Figure 1 is a perspective view of a display case, here shown in the form of a refrigerator but it will be understood that the invention may be 25 used in conjunction with show cases or other non-refrigerated display cases;

Figure 2 is a sectional view on line 2—2 of Figure 3;

Figure 3 is an enlarged sectional view on line 3—3 of Figure 1; and

Figure 4 is a sectional view on line 4—4 of Figure 3.

Heretofore display cases, both refrigerated and show cases, have been provided with illuminating means which are reflected in the glass panes through which the customer or prospective purchaser views the goods or food products therein. This reflected illumination is not only distasteful to the customer or prospective purchaser but 40 it likewise detracts from the displayed goods or food products. This invention relates particularly to means for not only effectively illuminating the displayed goods or products within the case but also to means preventing visible reflection 45 on the panes of glass of the case.

Referring then to the drawings in which like parts are designated by the same numerals in the several views, the case 1, here shown as a display refrigerator, has the conventional multiple spaced insulating glass panes 2, 3 angularly disposed therein, permitting customers and prospective purchasers to view the food products displayed within the refrigerator. Sliding doors 4 55 likewise provided with multiple spaced insulating

panes of glass 5, 6 are disposed at the rear of the case to afford access to the interior thereof.

The top member 7 preferably of porcelain clad metal, has a depending U-shaped plate 8 at each of its ends having bolt-receiving apertures substantially medial thereof and the opposite ends of these U-shaped plates are secured to the under side of the top member in any suitable manner as by spot welding, as best seen in Figure 3. A bolt 10 passing through the aperture of the U-shaped members and suspended therefrom, passes through an aperture of brackets 11 secured to each end of the case as by screws 12 and wing nuts 13 detachably secure the top member to the case.

This top member projects laterally and forwardly of the case and is provided with a depending or overhanging portion 14 lying adjacent the inner longitudinally disposed forward frame member 15 of the case and forming a canopy 75 forwardly of the spaced angularly disposed glass panes 2, 3. The inner side of the frame member 15 is non-reflecting in character, its surface being covered with a dark fabric 16 or the like secured thereto in any suitable manner or if 80 desired, the surface may be blackened.

A light shield 17 projecting laterally from the depending outer end of the top member toward the angularly disposed glass panes 2, 3 is pivotally secured to the lower edge of the depending outer end 14 of the top member 7 and is upwardly swingable to the position shown in dotted lines in Figure 3 to give access to the incandescent lamp 18 secured within its socket 19 mounted on the bracket 20. A conduit 21 for 90 the electric wiring 22 connected with the lamp socket projects through an opening 23 at one side of the case as best shown in Figures 2 and 4.

It will thus be seen that the top member 7 forming a canopy and the tilttable light shield 95 17 projecting laterally from the lower edge of its overhanging portion 14 forms a recess for the incandescent lamp 18 and its socket 19 and that access to the recess for inserting or replacing the lamp 18 is had by manually tilting the light shield 17 upwardly as indicated by dotted lines in Figure 3.

The lamp which is located exteriorly of the refrigerated interior of the case so that refrigeration is unimpaired by heat generated thereby, 105 provides illumination of the food products within the interior of the display refrigerator and the non-reflecting character of the fabric covered or darkened surface of the frame member, together with the light shield, prevents visible 110

reflection of the illuminating means upon the panes of glass within the vision of a customer or prospective purchaser viewing the food products displayed within the refrigerator.

5 While but one specific embodiment of this invention has been herein shown and described, it will be understood that numerous details of the construction shown may be altered or omitted without departing from the spirit of this invention as defined by the following claims.

I claim:

1. In a display case having a glass pane therein and lighting means disposed adjacent said pane and exteriorly thereof for illuminating the interior of said case, of means for preventing visible reflection of said lighting means upon said pane comprising a canopy mounted upon said case and disposed over said lighting means, and a light shield pivotally connected adjacent the lower edge of said canopy and projecting laterally therefrom toward said pane and below said lighting means.

2. In a display case having a glass pane therein and lighting means disposed adjacent said pane and exteriorly thereof for illuminating the interior of said case, of means for preventing visible reflection of said lighting means upon said pane comprising a top member for said case in the form of a canopy projecting forwardly therefrom and disposed over said lighting means, and a light shield pivotally connected to the lower edge of said canopy and projecting laterally therefrom toward said pane and below said lighting means.

3. In a display case having a glass pane therein and lighting means disposed adjacent said pane and exteriorly thereof for illuminating the interior of said case, of means for preventing visible reflection of said lighting means upon said pane comprising a top member for said case projecting laterally and forwardly therefrom and having a depending outer end disposed over said lighting means, and a light shield pivotally connected to said depending outer end and projecting laterally therefrom toward said pane and below said lighting means.

4. In a display case having a glass pane therein and lighting means disposed adjacent said pane and exteriorly thereof for illuminating the interior of said case, of means for preventing visible reflection of said lighting means upon said pane comprising a canopy mounted upon said case whose inner surface is non-reflecting in character and disposed over said lighting means, and a light shield pivotally connected to said canopy and projecting laterally therefrom toward said pane and below said lighting means.

opy and projecting laterally therefrom toward said pane and below said lighting means.

5. In a display case having a glass pane therein and lighting means disposed adjacent said pane and exteriorly thereof for illuminating the interior of said case, of means for preventing visible reflection of said lighting means upon said pane comprising a top member for said case projecting laterally and forwardly therefrom and having a depending outer end disposed over said lighting means whose inner surface is non-reflecting in character, and a light shield pivotally connected to said depending outer end and projecting laterally therefrom toward said pane and below said lighting means.

6. In a display case having a glass pane therein and lighting means disposed adjacent said pane and exteriorly thereof for illuminating the interior of said case, of means for preventing visible reflection of said lighting means upon said pane comprising a top member for said case projecting laterally and forwardly therefrom and having a depending outer end disposed over said lighting means whose inner surface is non-reflecting in character, and a light shield projecting laterally from said depending outer end toward said pane and below said lighting means and upwardly swingable with respect to said outer end to give access to said lighting means.

7. In an exteriorly illuminated refrigerator display case having insulating spaced angularly disposed glass panes, means for preventing visible reflection of the illuminating means upon said spaced panes comprising a canopy mounted upon said case and disposed over said illuminating means, and a light shield pivotally connected adjacent the lower edge of said canopy and projecting laterally therefrom toward said panes and below said illuminating means.

8. In an exteriorly illuminated refrigerator display case having insulating spaced angularly disposed glass panes, means for preventing visible reflection of the illuminating means upon said spaced panes comprising a top member for said case projecting laterally and forwardly from said angularly disposed glass panes and having a depending outer end disposed over said illuminating means whose inner surface is non-reflecting in character, and a light shield projecting laterally from said depending outer end toward said panes and below said illuminating means and upwardly swingable with respect to said outer end to give access to said illuminating means.

GEORGE J. HOPKINS. 130
